VIBRATORY SCREENING APPARATUS

Kurt Müller, Nordstr. 32, Recklinghausen, Germany

Filed Dec. 23, 1957, Ser. No. 704,837

2 Claims. (Cl. 209—365)

Schieferstein screening machines, that is screening machines which operate on the system of two masses and which are built up from separate sections supported on cushioning springs, are known, in which the screen elements are mounted on transverse beams which in turn are oscillatable in pivot bearings on both sides. The pivot bearings are mounted for rotation in the base frame members. For maintaining in central position the inclined suspended screen frame support elements, which are pulled downwards by the force of gravity, so-called anti-gravity springs are used. The arrangement of these anti-gravity springs in the known Schieferstein screening machines has not always been solved in a satisfactory manner; in particular the central or middle position of the inclined suspended screen frame support elements is not always ensured or adjustable for any angle of throw and the mass equilibrium of the whole apparatus is destroyed when the length thereof is changed by connecting up or disconnecting the individual sections.

The invention has for its object to ensure the central position of the screen frame elements suspended at an incline at all angles of throw and to enable changes to be effected in the length of the whole apparatus by connecting up or disconnecting individual sections, without disturbing the mass equilibrium.

The invention relates to Schieferstein screening machines composed of separate sections supported on cushioning springs, in which the screen frame elements are mounted on transverse beams and the latter are oscillatably arranged at both ends in pivot bearings which have their running fit in the base frame members, and this invention consists in adding anti-gravity springs to take up the mass weight of the transverse beams and the screen frames, and these are arranged at the ends of the transverse beams. A preferred form of construction is characterized by the fact that the springs are adjustable between the spacer guides of the pivot bearings.

An embodiment of the invention is illustrated by way of example in the accompanying drawing, in which:

Fig. 1 shows the screening machine in side elevation; Fig. 2 shows a pivot bearing on a larger scale;

Fig. 3 is a section taken on line A—A of Fig. 2; and

Fig. 4 shows a diagrammatic sketch of the operation of the invention.

The screen frame elements 1 of a screening machine composed of seven separate sections arranged in series and resiliently interconnected, are mounted on transverse beams 2, which are oscillatable in bearings 4, by means of link springs 3. The pivot bearings 4 are mounted for rotation in base frame members 5 and can be adjusted for a great variety of angles of throw. Anti-gravity springs 7 provided with clamping heads 8 are rotatably secured on the ends of the transverse beams, composed for example of carrier tubes, by means of welded-on journals 6, and are seated in a spring plate 9 which is slidable on spacer guides 10 of the pivot bearings 4 and firmly seated with the aid of nuts 11. Between the counter oscillating masses 1 to 2 and 4 to 5, accumulator springs

2

12 are provided which are mounted also in the pivot bearings.

The whole apparatus is mounted on cushioning springs 13.

5 The novel construction and arrangement according to the invention render it possible to impart to the anti-gravity springs 7 the pretension necessary for any angle of throw to exert a pressure corresponding to the gravity components of a transverse beam with its screening element, until the individual screening elements are brought into central balanced position.

Fig. 4 shows the action of a typical Schieferstein screening system using the particular anti-gravity springs of this invention. The path of operation of the screen is seen 15 in Fig. 4 by following the solid line from the upper left-hand corner to the lower right-hand corner. From one extreme position to another the springs are under compression, i.e., the upper accumulator spring, as shown, reaches its lowest point of compression, and then there 20 is a short transverse interval of play until such a time as it crosses the middle or central position, taking up the play on the lower side. At this point the manner of operation is along the dotted line, which is actually the anti-gravity spring line. This is an additional spring which 25 is added to the system in order to provide for additional resistance on the lower side and to overcome the effect of gravity upon the system. Instead of the normal upper line, which is shown in the lower right-hand corner, the accumulator spring line, the combination curve of the 30 accumulator spring and the anti-gravity spring should be noted because the force of the combination for any particular distance is always greater than the same distance for the upper accumulator spring. In this view, the upper half oscillation of the screen is shown in the upper 35 lefthand corner, while the lower half oscillation is shown in the lower right-hand corner.

To more fully understand the operation of this invention, the two-mass Schieferstein screening machine should be described as consisting of seven units supported 40 on insulating springs 13. Each unit is a two-mass system in itself, which is composed of a vibrating mass having spring frame elements 1 and transverse beams 2 and a counter oscillating mass having pivot bearings 4 in the base frame members 5. The screen frames are connected to the transverse beams 2 which at the ends are suspended in pivot bearings 4. These pivot bearings are adjustable and can be moved around the unit. At each pivot bearing the accumulator springs 12, of 45 rubber generally, on both sides of the transverse beam, are mounted so that they may be oscillated from a central or middle position upwardly and downwardly, perpendicular to the link or leaf springs 3. In the drawings the amount of play which takes place between the transverse beam and the accumulator spring is shown. Furthermore, according to this invention, the anti-gravity springs 50 are mounted to each pivot bearing 4 (see Figs. 2 and 3) to the journals in a direction perpendicular to the link or leaf springs. This arrangement of anti-gravity springs practically affects the lower half of the oscillation of this 55 screening system, and does so by providing a combination of the accumulator spring and the anti-gravity spring to carry a double effect. The anti-gravity springs take over the gravity component of the oblique suspended mass. This results in a combination of the oscillations of the 60 anti-gravity springs 7 with the unharmonic oscillations of the accumulator springs, as seen in connection with Fig. 4.

By way of example, a weight of the oscillating mass can be divided into a component parallel to the link springs 70 and into the gravity component in the direction of the anti-gravity spring 7. In a typical oscillation as seen in Fig. 4, there is a certain amount of play in the system

from the middle or central position of the vibrating system between the oscillating masses and the accumulator spring. This motion or play is a characteristic feature of the unharmonic vibration process and is intended. The size of such motion or play is adjustable. The anti-gravity springs set the central position of the oscillating mass, and a more regular striking of the oscillating masses to the accumulator springs is possible. This more regular action results in prolonged durability of the accumulator springs and, as well, a new combination of the anti-gravity and accumulator springs improves the mass compensation of the total system.

The advantage of this system is that each one of the separate screen sections may be centered at a different angle. The anti-gravity springs can be adjusted for the particular component of gravity involved. These may be adjusted to fit the screens in question so that the natural tendency of the springs to sag with the weight thereon will be offset. This is true not only of the static condition but of the dynamic condition also. Balance is thus achieved with the particular conditions on the screen.

Another advantage of the novel arrangement of the anti-gravity springs is that the mass equilibration of the whole machine is not disturbed even in the event of subsequent change in the total length thereof by connecting up or disconnecting individual sections.

I claim:

1. A vibratory screening apparatus of the counter os-

cillating type supported on cushioning springs and composed of a plurality of individual sections, each of which is composed of a pair of longitudinal base frame members, a transverse beam with a screening frame element secured on said beam, pivot bearings mounted for rotation in the longitudinal base frame members and supporting said transverse beam at both ends with said pivot bearings, each having mounted therein an accumulator spring and in addition each containing an anti-gravity spring between the transverse beam and structure of the pivot bearing, said anti-gravity springs being arranged to absorb the mass weight of said supports and screening elements.

2. The vibratory screening apparatus of the counter oscillating type as set forth in claim 1, wherein the pivot bearings are provided with spacer guides and the adjustable anti-gravity springs are arranged between these spacer guides and the transverse beam.
